UNITED STATES PATENT OFFICE.

RICHARD SMITH, OF BELLOWS FALLS, VERMONT, ASSIGNOR TO SMITH
PAPER MACHINERY COMPANY, OF PORTLAND, MAINE.

FEED MECHANISM FOR CALENDER-ROLLS OF PAPER-MAKING MACHINES.

SPECIFICATION forming part of Letters Patent No. 743,403, dated November 3, 1903.

Application filed January 3, 1903. Serial No. 137,757. (No model.)

To all whom it may concern:

Be it known that I, RICHARD SMITH, a citizen of the Dominion of Canada, residing at Bellows Falls, in the county of Windham and State of Vermont, have invented certain new and useful Improvements in Feed Mechanism for Paper-Making Machines, (Calender-Rolls,) of which the following is a specification.

My present improvements are based upon a method of conducting the paper of paper-making machines through the calender-rolls thereof, (shown and described in Letters Patent of the United States No. 327,031, issued to myself on the 29th day of September, 1885,) which consists in the employment with a stack of rolls of a series of alternately oppositely disposed curved deflector or guide plates which are practically concentric with and partially surrounding said rolls, these guide-plates functioning to automatically conduct the end of the paper sheet between the rolls, and thereby avoid danger to the machine tender, as well as to reduce to the minimum the amount of broken paper resulting from the "mending up," so called, of a break in the paper.

These improvements will be seen to consist in the construction of the "doctor"—that is, the device employed to prevent the winding of the paper about the roll, as well as to scrape from the surface of the roll any foreign substances which might otherwise adhere thereto—and also in the manner of mounting the said doctor and in the construction of the mechanical devices by which the latter is operated or adjusted.

In carrying out these improvements I construct the body of the doctor in tubular form (either cylindrical or angular in cross-section) and of wrought sheet metal in lieu of cast metal, as heretofore, by which construction I obtain lightness, which enables the doctor and its supports to be easily handled, and rigidity and stiffness, which obviates the liability to sag and crack to which the cast metal is subject.

My hollow doctor is provided at its ends with trunnions which rest in adjustable bearings supported by the housings of the machine-frame, by which means I am enabled to

apply or remove the doctor with ease and celerity.

The mechanical devices for supporting and for adjusting the doctor to the periphery of the roll consist in mounting each of its trunnions upon a vertically-adjustable carrier which is supported by and is susceptible of vertical adjustment upon vertical rods or bars secured in a suitable manner to the housings of the machine-frame, and in the combination, with such carrier, of two elastic mediums, which function, one to effect an automatic adjustment of the entire doctor bodily toward the roll and the other to effect an automatic adjustment of the scraper-blade of the doctor upon the body thereof with respect to said roll, by which constant contact between the scraper and roll is maintained.

To prevent lifting or jumping of the doctor in its bearings, I employ a horizontal locking-latch or turn-button, which constitutes the upper end of a vertical rod which is vertically adjustable within a bracket or extension formed upon or secured to the inner side of the trunnion-carrier before named, the free end of said latch extending (in its locked position) over and upon the top of a lug secured laterally to the body of the doctor.

For security the under side of the free end of the latch may carry a spur to enter a corresponding depression countersunk in the top of the lug before named, by which means accidental release of the latch is prevented. To provide means for lifting the latch when it is to be released, I employ in the present instance a horizontal hand-lever or shipper, which is pivoted at its base to the lower part of the trunnion-carrier and is swiveled in any suitable manner to the lower end of the rod before named as carrying the latch. The outer edge of the scraper-plate is secured rigidly to a light horizontal bar extending the entire length of the calender-roll, the inner or free edge of the said scraper-plate bearing as a

matter of course against the under side of the roll and as shown in my Letters Patent before cited. The horizontal bar is in turn secured to the inner edge of a horizontal plate of equal length, the outer edge of this plate being secured to the top of the body of the doctor.

100

To effect automatically a pressure or adjustment of the scraper-plate directly upon the calender-roll through the agency of the latch upon the lug, rock or slightly turn the body of the doctor upon its trunnions, and crowd the scraper-plate against the roll, as well as to prevent accidental lifting and unlocking of the latch, I employ in the present instance a coiled or other spring which is contained within the bore of the tubular bracket before named and surrounds the latch-carrying rod, the stress of such spring being exerted between a shoulder upon said rod and a nut screwed within the mouth of the bore of the bracket and operating by depressing the latch upon the lug before named to rock the doctor upon its trunnions and force the scraper up to the roll, as well as to prevent accidental lifting and unlocking of the latch.

To effect the desired adjustment of the doctor and its supports bodily toward the calender-roll, I employ in the present instance a coiled spring which functions between the under side of the trunnion-carrier and a collar secured to a vertical column which extends from top to bottom of the housings of the machine-frame and is secured to such housings in any suitable manner, this column constituting the main support of the doctor and its adjuncts.

The drawings accompanying this specification represent in Figure 1 a side elevation, and in Fig. 2 an end elevation, of a stack of calender-rolls of a paper-making machine broken away at the top. Fig. 3 denotes a vertical section of the devices for supporting the doctor in position, while Fig. 4 is a plan of the latter. Fig. 5 is a front view, Fig. 6 a side elevation, and Fig. 7 a plan, of the lower scraper and its supports. Fig. 8 is a vertical cross-section of an alternative form of construction of the body of the doctor. Fig. 9 is a perspective view of the bearing-plate having a slot in it to receive one of the trunnions of the lowest scraper. Fig. 10 is a horizontal section of one end of the body of the doctor, showing the manner of constructing the trunnions of the latter. Fig. 11 is an isometric elevation of one end of the body of the doctor and the parts immediately connected therewith.

In the above-named drawings, 11, &c., denote a series or stack of calender-rolls of a paper-making machine, the housings of the frame which supports such rolls being shown at 22, respectively, such housings to be united by cross-beams in the usual manner.

The body 4 of each doctor consists of a hollow tube, preferably cylindrical in cross-section and provided at its opposite ends with trunnions 5, which may be formed integral therewith, but which in practice I cast separately and insert within the ends of the tube, as shown in Fig. 10 of the drawings. Each trunnion 5 is supported in a box or bear-

ing which forms part of or is secured to a vertical plate or carrier 7, this carrier having a tubular portion or hub 8 cast integral with it or bolted to it and which incloses and is susceptible of vertical adjustment upon one of the columns 3 before named.

Each doctor is prevented from "jumping" or rising in its bearings by a horizontally-adjustable locking-latch 10, which is a horizontal arm or turn-button secured at its base to the upper end of a vertical shaft or rod 11, which is contained and is susceptible of slight vertical play within the bore of a tubular bracket 12, formed upon or secured to the inner side of the trunnion-carrier 7, the free end of this latch (when in a locked position) bearing upon the top of a lateral lug 13, secured to the body of the doctor. For security the under side of the free end of the latch 10 may carry a spur 14 to enter a corresponding countersunk depression in the top of the lug 13, this spur preventing accidental turning and unlocking of the latch.

To effect the lifting of the latch 10 against the stress of the spring which tends to depress it, I employ in the present instance a horizontal hand-lever or shipper 16, which is pivoted at its base to the lower part of the trunnion-carrier 7, as shown at 7', and is swiveled in any suitable manner to the lower end of the rod 11.

When it is desired to remove a doctor, the rod 11 is by means of the hand-lever 16 raised, the latch 10 turned to one side, and the trunnions of the doctor left free to be lifted out of their bearings.

The scraper-plate of the doctor, which is shown at 17, is secured at its outer edge to a light horizontal bar 18, extending the entire length of the calender-roll, the inner or free end of this scraper bearing, as before premised, upon the under side of the roll. The bar 18 is in turn secured at its outer edge to the inner edge of a plate 18' of equal length, the outer edge of this latter plate being secured to the body of the doctor 4.

As the scraper 17 is in itself in common use and its purposes well understood, further reference directly to it will not be made.

To effect automatically the adjustment or advance of the doctor and its supports bodily toward the calender-roll, I employ in the present instance a coiled spring 9, which encircles a column 3 and exerts its stress between the under side of the carrier 7 or the hub 8 of the latter and a collar 8', secured to said column.

To effect an automatically-adjustable pressure of the scraper 17 directly upon the calender-roll through the agency of the latch 10 acting upon the lug to depress the rod 11 and the latch, rock or slightly turn the doctor upon its trunnions, and thereby crowd the scraper again to the roll, as well as to prevent accidental lifting and possible unlocking of the latch, as before premised, I employ in the

present instance a second coiled spring 22, which is contained within the bore 23 of the bracket 12 and surrounds the latch-carrying rod 11 and exerts its stress between a shoulder 23', formed upon such rod, and a nut 23", screwed within the mouth of the bore 23 and surrounding such rod, the spring acting through the pressure of the latch upon the lug 13 to rock the doctor upon its trunnions, 65
 5 o as stated, the spring 22 furthermore serving to maintain the latch in contact with the lug, and thereby prevent unlocking of said latch, as before stated.

The lower inner side of the body of the 70
 15 doctor is a curved plate 22², which is practically a segment of a circle struck from the center of the calender-roll, this curved plate serving in part to direct the paper sheet between the rolls, the guide-plate proper being 75
 20 shown at 24 as depending from the under side of the body of the doctor. They may be of one sheet of metal with the plate 22² or independent of the latter, which is secured at its inner edge to the under side of the bar 18, 80
 25 before named, and at its outer edge to the under side of the tube 4 of the doctor.

The tube 4 and plates 18' and 22² constitute a trussed body of great strength and lightness.

30 The supports of the lower protector-plate 17, which serve to finally take off the paper from the calender-rolls, are constructed similarly to those of the doctor in so far as the employment of the rod 11, spring 22, hand-lever 16, and latch 10 are concerned, with the exception that they are reversed in position, top for bottom, while the trunnions of the tube 4 are journaled each in a circular plate 31, confined to the carrier-plate 7 by set 85
 35 screws or bolts 32, operating with concentric slots 33, formed in the said plates 31. The groove for receiving each trunnion is, as shown in Fig. 9 and in dotted lines in Fig. 6 of the drawings, composed of a vertical entrance-way or passage 34, open at top and terminating at bottom in a lateral horizontal extension or pocket 35. The shoulder 36 of the groove 34 36 prevents accidental lifting and escape of the trunnion. 90

40 50 An alternative form of construction of the body of the doctor is shown in Fig. 8 of the drawings, in which the said body is tubular; but in lieu of the cylindrical portion 4 and the plates 18' and 22², as before described, the body is triangular in cross-section. The preferred shape is triangular, as shown, the said body being composed of three plates or sides—viz., an upper horizontal plate 27, an outer upright plate 28, an inner plate which is composed of the curved guide-plate 24, before named, the inner edges of 27 and 24 being secured to the bar 18 and the lower edge of 28 secured to said guide-plate 24, while the outer 100
 45 55 60

edge of 27 and the upper edge of 28 are bolted together. The three plates 24, 27, and 28 secured together provide a trussed construction which, like that shown in the tube 4 and plates 18' and 22², is at once very light, stiff, and strong. When the said body is quadrangular, pentagonal, hexagonal, or of other 70
 65 angular shape in cross-section, the number of such plates must, of course, be correspondingly increased.

Fig. 10 denotes the manner in which I prefer to construct the trunnions of the body of the doctor, which consists in casting them independent of such body 4, the trunnion proper, 5, being an extension of a body 37, which is of a diameter to tightly fill the end of the body 4, into which it is tightly driven. 80

To enable the machinist in setting up a stack of calenders or applying a doctor to a stack to rapidly and temporarily ascertain approximately the final position of the doctor, the trunnion-carrier 7 may be made independent of the hub 12 (by which it is supported, in position on the column 3) and the two connected by a spline and groove, as shown at 37 in Fig. 11 of the drawings, and when the permanent position of the doctor is found the two are bolted together, or the spline and groove may be vertical.

I claim—

1. A tubular doctor provided with trunnions, in combination with the guide-plate and scraper-plates which it supports, a latch for locking the said doctor in position, and automatic normally operative means independent of the said latch, for crowding the scraper-plate directly upon the roll substantially as set forth. 95

2. In combination with a doctor, a spring-pressed latch bearing on a part thereof to hold the said doctor from rising in its bearings substantially as set forth. 105

3. In combination with a calender-roll, a doctor, a scraper carried thereby, a spring which forces the doctor bodily toward the calender-roll and an additional spring which acts to rock the doctor upon its trunnions toward the said calender-roll substantially as set forth. 110

4. The mechanical devices herein described for supporting and operating the doctor, consisting of the carrier which carries the journals of the the tubular body of the doctor—the spring for actuating said carrier, and the adjustable latch for locking the doctor-body in position and carried by the spring-actuated rod, substantially as explained. 115
120

In testimony whereof I affix my signature in presence of two witnesses.

RICHARD SMITH.
